UNITED STATES PATENT OFFICE.

THOMAS R. LOWERRE, OF MOTT HAVEN, NEW YORK.

LETTER-BOX.

SPECIFICATION forming part of Letters Patent No. 277,586, dated May 15, 1883.

Application filed November 23, 1882. (No model.)

To all whom it may concern:

Be it known that I, THOMAS R. LOWERRE, a citizen of the United States, and a resident of Mott Haven, in the county of New York and 5 State of New York, have invented certain new and useful Improvements in Letter-Boxes, of which the following is a specification.

My invention relates to improvements in devices for notifying the public, after each collection of the mail from a letter-box, of the hour when the next collection will be made, and for controlling the attentiveness of the mail-carrier by making it appear whether or not he neglected to make the previous collection 15 at the proper time indicated on the time-table, according to the rules of the post-office, and for protecting the time-table from injury by being defaced or washed off by rain. An invention for the same purpose was patented 20 to me by the United States Patent Office May 11, 1880. In public use of the said invention it has been found expedient to leave the time-table permanently in the box and to exchange at each collection only the card or portion of 25 the time-table which indicates the hour of the next collection. It has been found, however, that, owing to the differences in the changes of the temperature between the exterior atmosphere and that inclosed in the box, the 30 glass "sweats," as it is termed; or moisture condenses upon its inner surface, thus dampening the face of the time-table, which thereby in a short time becomes uneven, moldy, and partly or wholly illegible. The location of the card-pocket, as at present arranged, in the upper 35 edge of the time-table pocket, exposes the card to rain when the door is opened by the collector or in wet weather, and the friction produced by constant changing of the tag or card against 40 the inner surface of the glass abrades the latter, and in time makes the tag less legible.

The object of my present invention is to remove the aforesaid objections.

In the accompanying drawings, Figure 1 45 represents a front view of an ordinary street letter-box provided with my present improvements. Fig. 2 is a horizontal section taken on the line xx of Fig. 1, and drawn to a larger scale. Fig. 3 is a front view of a portion of the same and of the stationary time-table, showing 50 the removable tag. Fig. 4 is an edge view

of the door, partly in section, through the line yy of Figs. 2 and 3, the said Figs. 2, 3, and 4 being drawn to the same scale. Fig. 5 is an inside view of the door, drawn to a smaller 55 scale than any of the previous figures. Fig. 6 is a detail cross-section of a modification of the air-tight pocket for containing the stationary time-table.

Similar letters of reference indicate like parts 60 in the several figures.

A is the box. B is the door of the same, provided with a square opening forming a frame, which is rabbeted on the inside to receive the glass plate C, behind which the time-table D 65 is permanently placed, and covered on the inside with another glass plate, E. Between the edge of the outer pane, C, and its contact-surface with the frame or pocket b of the opening in the door is inserted a rubber or other 70 water-tight packing, c , and similar packings, $d e$, are inserted between the two glass plates C and E and behind the inner plate, E, respectively, after which the solid backing-plate F, fitting the perimeter of the said rabbet, is 75 inserted from the inside, as shown in Figs. 2 and 4, and secured to the door by screws or other suitable fastening, said plate F, when so secured, pressing upon the inner packing-ring, e , and thus compressing the three packings c and the two glass plates together in the rabbet b , so that no moisture can ever enter between the said glass panes to damage the time-table, D. Instead of the three separate packings $e d c$, the same effect may be 85 produced by stretching a rubber band completely around the edges of each of the glass plates.

In the metallic back plate, F, opposite the lower right corner of the opening of the time-table, a recess or pocket, f , is formed for receiving the tag G, indicating the time for the next collection, which tag is slid into the said pocket or recess from the side, a portion of the plate F being cut away at f' to give access, by 90 the thumb or finger of the collector, to a slot, g , in the outer end of the tag G, for withdrawing the same from the said recess or pocket and replacing it with another bearing the date of the next collection. A thin rigid frame, H, 95 secured to the back F by screws h , forms a frame covering the tag-pocket on the outside,

and when the plate F is secured to the door the said frame H prevents the tag G from coming in contact with and wearing the inner surface of the pane E. In order to make the tag G durable and prevent the possibility of defacing the figures and letters thereon, the same is made of a piece of metal and the figures stamped through the same, in the manner of an ordinary stencil-plate, and the back of the recess f is painted with a different color, contrasting with the color of the tag, so as to make the stencil-figures plainly visible from the outside.

Instead of making the water-tight time-table chamber in the manner above described, the same may be made, as shown in Fig. 6, by forming it of a glass vessel or flattened bottle, I, suitable to receive the time-table, and having but one side opening, through which the said time-table may be inserted, which opening may then be closed by a tight-fitting cork or other stopple, i. It will be seen that the pocket for receiving the tag G, and which is covered by the plate-frame H, forms a part of the back plate, F, and is entirely independent of the glass plates C E and the rabbet b.

It should be observed that the lower corner of the time-table must be cut away to form a suitable opening opposite the pocket f to allow of reading the tag G.

Having thus described my invention, I claim as new and desire to secure by Letters Patent—

1. In a letter-box, a time-table chamber visible through an opening in the said box, said

chamber being formed of an outer and an inner pane, C E, and an air-tight connection between the said panes at their edges, substantially as and for the purpose set forth. 35

2. The combination, with a letter-box having a rabbeted opening, substantially as described, of a time-table chamber formed of the panes C E, and air-tight packings c d e, and the back plate, F, for the purpose herein set forth. 40

3. The combination, with a time-table chamber constructed substantially as described, and visible through an opening in the letter-box, of the back plate, F, provided at its lower corner with a pocket, f, for receiving and exposing the tag G, substantially as and for the 45 purpose herein set forth. 50

4. In a letter-box, the combination, with a door, B, having a rabbeted opening and an air-tight time-table chamber within the said opening, substantially as described, of the back 55 plate, F, provided with the tag-pocket f, and the frame H, secured to the said back plate in front of the said pocket, for the purpose herein before set forth.

In testimony that I claim the foregoing as my 60 invention I have signed my name, in presence of two witnesses, this 20th day of November, 1882.

THOMAS R. LOWERRE.
